UNITED STATES PATENT OFFICE.

ERNEST H. THOMPSON, OF NEW YORK, N. Y.

FARE-REGISTER.

1,297,274.

Specification of Letters Patent. Patented Mar. 11, 1919.

Application filed April 8, 1914, Serial No. 830,384. Renewed June 15, 1917. Serial No. 175,040.

To all whom it may concern:

Be it known that I, ERNEST H. THOMPSON, citizen of the United States, and resident of New York, county of New York, and 5 State of New York, have invented certain new and useful Improvements in Fare-Registers, of which the following is a specification.

This invention relates to fare registers 10 for street railway cars and the like, and is intended to provide a simple and reliable means for registering automatically each cash fare deposited in the fare box, provision being also made for registering, on 15 the same register, transfer fares or slips received.

In its general aspects the invention embraces a dial indicator one member of which is actuated, step by step, as each cash fare 20 is deposited in the fare box, electrically actuated mechanism being set in motion automatically by the coin deposited to effect this purpose. Another feature of the invention consists in the combination with the electrically 25 operated dial indicator, with electrically controlled means for returning the dial indicator mechanism to zero, such re-setting means being manually controlled and preferably so related to the fare box, that 30 its removal for re-location at the other end of the car acts automatically to restore or re-set the register at zero.

Another feature of the invention consists 35 in the construction and arrangement of the ratchet mechanism by which the capacity of the register is increased without unduly enlarging the dial or making the ratchet teeth too fine for reliable work.

These and other features of the invention 40 will be more particularly explained in the specification following, and more precisely defined in the claims annexed hereto.

In the accompanying drawings—

Figure 1 is a plan view of the electrically 45 operated fare register with the cover removed to show the interior arrangement;

Fig. 2 is a transverse central section of the apparatus shown in Fig. 1;

Fig. 3 is a detail view of the double brake 50 pawl for the two ratchet disks;

Fig. 4 is a sectional side elevation of a fare box showing the electrical connections and the two circuit closing devices by which the cash fares and the transfers respectively 55 are registered;

Fig. 5 is a detail in front elevation show-

ing the totalizing registers used in connection with the circuit closers;

Fig. 6 is a diagrammatic view showing the course of the circuits to the electromagnets;

Fig. 7 is a front view of the dial indicator on a reduced scale.

In practice it is my intention to provide an overhead fare register, visible to the occupants of the car, which so far as the cash fares paid is concerned, is independent of the control of the conductor. Inside the fare box itself, and also out of the control of the conductor, are totalizing registers 70 which form a permanent record, whereas, the large overhead register is provided with means for being restored to zero position at the end of each run or trip, whenever desired. The preferred mode of restoring 75 or re-setting the indicator to the zero mark is by the closing of a circuit automatically when the fare box is removed for replacement at the other end of the car for the return trip.

It will be understood that the fare box is of the type shown and described in my co-pending application for automatic coin box, filed on the 24th day of October, 1913, and only so much of said fare box and its 85 mechanism is shown herein as is needed to make clear the operation of the present invention.

I will first describe the overhead fare register intended to be visible to the occupants of the car. This comprises a suitable casing *a*, in which is mounted a central arbor or shaft *c'* which supports in this case two rotatable ratchet disks *b* and *c*, to each of which is connected an independent pointer 90 *b*² and *c*². The pointer *b*² is secured to the rotatable shaft *c'* which by means of a set screw *b*³, is secured to the hub of the ratchet disk *c*, and is intended to register the cash fare deposited. The pointer *c*² is secured 100 directly to the hub *c*²² of the ratchet disk *b* and is intended to register transfer slips.

Each of the ratchet wheels *b* and *c* is operated by its own individual electromagnet. The ratchet *b* is engaged by the pawl *b*⁴, 105 and normally held out of engagement by means of the retractile spring *b*⁵. A guide and stop post *b*⁶ is provided to make it impossible for the pawl to move the ratchet wheel more than one tooth at a time, the 110 pawl being crowded in between the guide post *b*⁶ and the ratchet wheel as it advances,

so as to prevent the following tooth from passing by. This feature is important because the quick jump of the pawl, produced by the energizing of the electromagnet b^7 gives a considerable impulse to the ratchet wheel. The pawl b^4 is carried by a swinging arm b^8 normally held retracted by means of the spring b^5 , but which is so arranged as to be attracted by the magnet when energized, so as to advance the ratchet wheel b step by step, through the engagement and movement of the pawl b^4 .

The circuit which energizes the electromagnet b^7 is controlled by means of a circuit closer or oscillatory switch member d , which has an insulated face d^2 on which is mounted a short copper terminal or contact strip d^2 in position to engage the contact finger d^3 , so as to close the circuit passing through the electrodes or conductors x, y leading to the magnet b^7 .

In order to hold the ratchet wheel b against accidental or reverse rotation when the pawl b^4 is retracted or disengaged therefrom, I provide a brake pawl or detent g , which is normally spring pressed into engagement with the opposite side of the ratchet wheel b , so as to allow the ratchet to advance but hold it against reverse movement. The wheel b is returned to original or zero position by means of suitable mechanism, such as a clock spring g' , one end of which is secured to the hub of the ratchet wheel b , the other end being anchored to a fixed stud g^2 carried by the casing.

In a similar manner the transfer-registering ratchet disk c is actuated by the pawl c^3 , carried by the swinging arm c^4 , and is normally retracted by the spring c^5 . A guide post c^6 , similar to guide post b^6 , is employed to prevent a movement of more than one tooth at a time. The pawl c^3 and the arm c^4 are actuated by the electromagnet c^7 when energized. A clock spring h secured to a fixed stud h^1 on the cross bar h^2 , at one end, and to the hub of the ratchet wheel c at the other end, becomes wound up as the disk c is rotated by its actuating pawl c^3 , in the same manner as already described in reference to ratchet wheel b .

The brake or locking pawl g is made in two parts or double, as shown in Fig. 3, so that both may be simultaneously retracted by the T-arm g^5 which is mounted on the swinging armature arm e, e' , which is pivoted at its middle so as to extend in front of the electromagnets n and o . When the release rod g^5 is retracted it, of course, pulls both stop pawls g out of engagement with their respective ratchet wheels b and c , and the ratchet wheels are then reversely rotated by their respective clock springs to the zero position. Obviously when the lower arm e is advanced away from the electromagnet n , the pawls g are in locking position.

The electromagnet o when energized tends to restore the lever e, e' to a position which allows the pawl g to interlock with the ratchet wheels, while the electromagnet n when energized swings the lever e back to release the pawls from operative engagement with the ratchet wheels. Usually the electromagnet n is intended to be operated only at the end of a run or trip, when the fare box is shifted to the other end of the car, consequently the circuit has to be closed only momentarily at that time for the purpose of disengaging the pawl g^5 . This is accomplished by making a switch connection between the terminals f, f' , the latter of which is mounted in a hollow post or coupling member p , formed on the bottom of the fare box which telescopes over a vertical post p' which carries the contact terminal f extending for a short distance from the top, below which is arranged the insulation f^2 . Consequently each time that the fare box is removed from its standard or replaced thereon, it closes the circuit f, f' thereby energizing the magnet n and allowing the ratchet wheels to reset to the zero point. Of course, any suitable form of manually controlled circuit closer can accomplish this purpose, but it is advantageous to do so in such a way that the removal of the coin box of itself automatically closes this circuit, thereby dispensing with reliance upon the memory of the conductor.

It is, of course, important that the pawl g should be returned to operative position before any fares are registered in order that the ratchet disks may not turn back to zero after being advanced to record one or more fares. This is accomplished by the energizing of the electromagnet o , as above explained, but as it is not desirable to have the electric current flowing continuously through the field of that magnet, I provide means for breaking the circuit and holding the arm e' in retracted position without the further aid of the electromagnet o , so as to allow the pawl g to remain in operative position. To this end the conductor leading to the field of the electromagnet o passes through a spring fork n' which forms one terminal or contact member of a switch, the other member of which switch consists of the contact rod or finger n^2 secured to the arm e' . The spring fork n' has oppositely curved or indented clamping jaws, as shown in Fig. 2, to receive and detain said contact finger when the arm e' is away from the electromagnet o by the pull of the electromagnet n . The spring tension or grip of the spring fork n' is not sufficient to withstand the pull of the electromagnet o when the latter is energized, consequently the circuit controlling this electromagnet o is broken, since the magnet is energized and the arm e' carrying the contact n^2 is held in retracted position by means of a

light tension spring n^3 , which is sufficient for this purpose, although not strong enough to overcome the grip on the spring fork n' .

I will now explain the action of the circuit closers which control the magnets o and c' . The circuit closer as shown in Figs. 4 and 5, comprises a rotatable or oscillating disk d provided with a peripheral stop or insulation d' , on which is mounted a strip d^2 which is movable into intermittent engagement with the coöperating contact finger d^4 , which is connected to the conductor d^5 which leads through the permanently closed contact d^6 to the conductor d^7 which is in circuit through the switch n' , n^2 with electromagnet o . Consequently each time that the circuit closer d is oscillated it acts to close or energize the circuit d^5 , d^7 , provided of course the switch at n' , n^2 is closed. Obviously if switch n' , n^2 is open there is no need of energizing the electromagnet o , since the switch at this point is open only when the arm e' is retracted and the pawl g is, therefore already in operative position, which it is the object of this circuit to insure.

The circuit for energizing the electromagnet c' is closed by means of the contact finger d^8 and the coöperating terminal d^2 , but it will be observed that the circuit between the members d^2 , d^4 and magnet o is closed slightly in advance of closing the circuit between the members d^3 , d^2 , and magnet c' so as to make certain that the locking pawl g is in operative position before the ratchet wheel is advanced a step, through the medium of the electromagnet c' .

The means for actuating or oscillating the circuit closing disk d comprises a lever m^2 having a pin m^3 suitably engaging a slot d^{10} in the disk d . This lever m^2 is connected by a link m^4 with the solenoid plunger m' mounted in the fare box m , which solenoid plunger is actuated electrically through the agency of the coin deposited in the coin chute m^5 , as explained in my co-pending application above referred to. The details of the coin-controlled mechanism of the fare box need not be herein described because they form another part of this invention and are described in the aforesaid application. It is sufficient to state that the coin deposited in the chute m^5 closes the circuit by means of which the solenoid is energized to retract the plunger m' and transfer the coin into the coin-receiving compartment, and as soon as the coin is removed and the controlling circuit broken, the spring m^6 acts to restore the plunger m' to initial position. Consequently by connecting the disk-actuating lever m^2 with this plunger, an oscillatory movement can be imparted to the disk d each time that a coin is deposited. Hence through the medium of the circuits x , y leading to the electromagnet c' the fare so deposited is registered on the dial indicator.

Provision has to be made also for registering transfer slips in order to make the device complete and practical. In this case, however, since it is not convenient to make the transfer slips automatically operative, the transfer registering pointer or ratchet obviously has to be made for the voluntary registering of the transfers by the conductor. To this end I provide a yielding spring pressed plunger i which engages a swinging arm i' carrying a pawl i'' engaging a ratchet wheel i^3 so arranged as to force a spring contact member i^5 upward into contact with an opposing spring member i^6 , thereby closing a circuit at that point. Now the contact i^5 is connected to the conductor d^5 and the contact member h^6 with wire d^{11} , so as to energize the electromagnet o in the same manner as in the case of the contact member d^4 , above described. As in the case of the contact member d^2 , so the contact member i^5 is capable of forming a double contact first with the member i^5 to energize the electromagnet o , and then, as it is pushed upward by the engagement and movement of the member i^5 , into engagement with the other contact member i^8 , which completes the circuit through the conductor d^{12} and w to energize the magnet b' , which actuates the ratchet wheel b for registering the transfer slips as they are deposited.

Thus it will be seen that each cash fare deposited acts automatically to advance the register one step, while the conductor on receiving and depositing each transfer slip actuates the transfer register by hand.

The dials for registering fares are usually divided into one hundred divisions, although occasionally more than a hundred fares are registered. Furthermore, as a stop has to be provided for preventing the reverse rotation of the ratchet wheels b and c beyond the usual point, I have provided means which allows the ratchet wheel to rotate through almost two revolutions for the purpose of registering faces, while providing stop mechanism that arrests the reverse rotation of the disk at zero. This is accomplished, as best shown in Fig. 1, where the ratchet wheel c is provided with a projecting stop pin c^{20} . Loosely mounted upon the central arbor is a radial arm or lever c^{21} , which at the zero position of the disk c is in position to the rear of the stop pin c^{20} . Consequently the disk c can make almost an entire revolution in the advanced direction before coming into engagement with the rear side of the arm c^{21} . After one complete revolution, therefore, the stop pin c^{20} in its further advance carries with it the lever c^{21} and can rotate approximately a complete revolution before the lever c^{21} comes into contact with the stop pin h' fixed to the cross bar h^2 in position to engage the front or advancing edge of the arm c^{21} . By this construction it

is possible to allow the ratchet wheel to rotate through nearly two entire revolutions and thus register nearly two hundred fares, while making adequate provision for stopping the reverse rotation at zero. This dispenses with doubling the size of the dial which would be inconvenient, or of making finer sub-divisions on the dial and on the ratchet, which would not be satisfactory 10 since the dial cannot be so easily read at a distance, which is important if not essential in this class of devices.

In the same manner the ratchet disk b may be provided with a stop pin b^{20} and a loose arm b^{21} engaging a fixed stop to accomplish the same purpose with respect to the fare registering pointer.

For exposing to view on the dial the word "In" and "Out" to indicate that the 20 register has been reset at the end of the trip, I provide a disk r carrying around its periphery in radial arrangement, the words "In" and "Out", which are exposed to view by an opening in the face of the dial, as 25 shown in Fig. 7. This disk r is mounted on an axial stud r' and carries a ratchet wheel r^2 , which is actuated by a pawl r^3 on the arm r^4 , which is secured to the oscillatory armature lever e, e' to be oscillated each time 30 that the ratchets or pointers are reset to the zero mark.

Of course, provision has to be made for connecting-up the electrical conductors, contained in the fare box leading to the various 35 circuit controllers therein, with the conductors leading outside of the fare box to the overhead register. This is accomplished by leading the interior wires to externally projecting contact members p which engage co-operating terminals p' suitably arranged on 40 projecting posts formed on the base which carries the fare box, so that when the fare box is set in position all connections are automatically made with the overhead register. As above pointed out one of these 45 connections, namely that at f, f' is a temporary connection made only when the fare box is set in place or when it is removed from the base. The other connections are as 50 indicated in the diagram, permanent so long as the fare box is in position on its base.

What I claim is:

1. Means for registering fares embracing in combination a fare box for receiving coins, 55 a fare register located at a distance therefrom, electrical connections leading from the face box to the fare register and means controlled by the coin deposited for automatically actuating said register to register 60 the fares deposited by controlling the flow of current through said electrical connections, substantially as described.

2. The combination of the fare box, an electrically actuated fare box register located 65 at a distance therefrom and having electrical

connections with said fare box, a circuit closer located within the fare box for controlling an electric circuit by which the register is operated, and means for closing said circuit to record the fare deposited, substantially as described. 70

3. The combination of a dial indicator, a ratchet and pawl for actuating the same step by step, an electromagnet for actuating said pawl and ratchet, a fare box and a coin-controlled circuit closer mounted in said fare box and arranged in circuit with said electromagnet in order to energize the same each time that a fare is deposited, substantially as described. 75

4. The combination with an electrically actuated dial indicator of a fare box, an oscillatory disk mounted therein to close the electric circuit by which said dial indicator is operated, and a coin-controlled member 85 for oscillating said disk into and out of circuit closing position, substantially as described. 80

5. The combination with a dial indicator and its actuating ratchet and pawl, a brake pawl acting normally to prevent reverse rotation of the ratchet, an electromagnet acting when energized to move said brake pawl into operative engagement with the ratchet, a supplemental electromagnet operating when energized to release said pawl from such engagement, substantially as described. 95

6. The combination with a dial indicator and its actuating ratchet and pawl of a 100 brake pawl to prevent reverse rotation of said ratchet, an electromagnet for moving said brake pawl out of operative relationship to said ratchet to permit the resetting of the indicator, a second electromagnet by 105 which said pawl is restored to operative position, means for automatically breaking the circuit in said latter electromagnet when the same is energized, and a spring for maintaining the brake pawl in operative position 110 when the last-named electromagnet is deenergized, substantially as described.

7. A fare register embracing in combination, a dial indicator and its actuating ratchet and pawl, an electromagnet for actuating said pawl to turn the ratchet step by step, a brake pawl to prevent reverse rotation of said ratchet, a magnetically controlled lever by which the movement of said 115 brake pawl into or out of operative engagement with said ratchet is controlled, a pair of electromagnets for moving said lever in opposite directions, and a circuit closer arranged to control the ratchet-actuating pawl and the ratchet-brake pawl, substantially as 120 described.

8. The combination with a dial indicator, a ratchet, an actuating pawl therefor, a brake pawl movable into and out of operative relationship to said ratchet, electromag- 125

nets for moving said pawls, a coin-controlled circuit closer arranged to energize successively the brake-pawl magnet and the ratchet-actuating magnet, substantially as described.

9. The combination with the ratchet, its actuating pawl, a brake pawl, an electromagnet for controlling each of said pawls, a movable circuit closer, and two insulated contact fingers in circuit with the respective magnets arranged to be successively engaged by the contact member of said circuit closer, substantially as described.

10. The combination with a dial indicator, an electrically actuated mechanism for operating said indicator, means for automatically resetting said indicator, a fare box, a supporting base therefor having electric connections with the indicator mechanism, said fare box being provided with an electric switch arranged to close the circuit governing the resetting means automatically when the fare box is removed or restored to its base, substantially as described.

11. The combination with the electrically actuated dial indicator for registering fares, a fare box, a supporting base therefor provided with electrodes connected with the indicator mechanism, circuit closer mechanism mounted in the fare box the terminals of which are arranged to form electrical contacts with the electrodes in the supporting base when the fare box is placed in position, while allowing the fare box to be removed, substantially as described.

12. The combination of the dial indicator, an actuating ratchet and pawl for moving the indicator step by step, means for resetting the indicator when desired, a stop pin secured to said ratchet, a loose pivoted arm 40 normally located to the rear of said stop pin during the first revolution of said ratchet, a fixed stop pin arranged to engage said arm after said arm has completed approximately one revolution about its axis, substantially as described.

13. The combination with the dial indicator of a rotatable ratchet and its actuating pawl, a spring tending normally to reversely rotate said ratchet, a brake pawl for 50 neutralizing the action of said spring, a movable stop mechanism arranged to allow said ratchet to rotate beyond one full revolution, while acting to arrest the reverse rotation of the ratchet at the initial or zero 55 point, substantially as described.

14. The combination of a dial indicator, its actuating ratchet and pawl, a brake member normally engaging the ratchet, and means for disengaging said brake member 60 to permit the ratchet to return to initial position, and a supplemental movable indicator actuated by said brake pawl mechanism, substantially as described.

In witness whereof, I have subscribed the 65 above specification.

ERNEST H. THOMPSON.
